UNITED STATES PATENT OFFICE.

CARL LUNDIN, OF PITTSBURGH, PENNSYLVANIA.

METHOD OF PRODUCING GAS.

Application filed January 18, 1922. Serial No. 530,129.

To all whom it may concern:

Be it known that I, CARL LUNDIN, a citizen of the United States, and a resident of Pittsburgh, in the county of Allegheny and State 5 of Pennsylvania, have invented a new and useful Improvement in Methods of Producing Gas, of which the following is a specification.

The invention relates to a method for producing gas. It relates particularly to a method for producing an artificial gas high in carbon monoxid and hydrogen.

The usual fuel or producer gas contains a relatively high percentage of non-combustible elements which reduce the heat efficiency of the gas. The non-combustible component of these gases is mostly made up of nitrogen which is present in the gas, due to the fact that the oxygen required for the 20 gasification of the coal is taken from the atmosphere. It is important that a simple, efficient method for producing gas be devised in which the gas produced is substantially free from nitrogen and high in desirable 25 combustible elements. In order to be commercially successful this process must require a minimum amount of heat and must be simple so that a complicated apparatus is not required for carrying it out.

One of the objects of the present 30 invention is to provide an improved process for producing a fuel gas which is substantially free from nitrogen, has a high percentage of combustible elements, and one in 35 which the heat generated in the production of the gas is utilized for carrying out the process itself.

A further object is to provide an improved process for producing a gas high in 40 carbon monoxid and hydrogen and substantially free from nitrogen by distilling carbonaceous material, out of contact with air, and furnishing oxygen to the gases produced by means of a metallic oxid, the heat of the 45 combustion caused by the uniting of the oxygen of the metallic oxid with the gases produced from the coal furnishing heat for carrying out the process.

Other objects and advantages will appear 50 from the following specification.

A process similar to the one disclosed herein in which the gases were necessarily passed in but a single stream to effect oxidation and in which the heat was absorbed in but a single stage after leaving the carbonaceous ma-

terial was disclosed and claimed in my prior application Serial No. 473,046, filed May 27, 1921, of which this application is a continuation in part.

Generally stated the process consists in the 60 destructive distillation of carbonaceous material, such as coal, to produce carbon monoxid (CO), hydrogen (H₂), and other gases, the percentage of each depending on the quality of carbonaceous material used; the 65 passing of these gases into contact with a metallic oxid, such as magnetic oxid of iron (Fe₃O₄) to change the carbon monoxid to carbon dioxid (CO₂), thereby producing heat for carrying out the entire process; and 70 the subsequent passing of the carbon dioxid over heated carbonaceous material to again change it to carbon monoxid; air being excluded from the entire process to exclude the non-combustible gases of the atmosphere, 75 such as nitrogen, from the gas.

The accompanying drawings show a form of apparatus for carrying out the process. In these drawings Fig. 1 is a diagrammatic view illustrating the arrangement of the 80 principal portions of the apparatus; Figs. 2, 3, and 4, illustrate the type of check valve used in the conduits of the apparatus, Fig. 3 showing the same in end elevation, and Figs. 2 and 4 showing the same in longitudinal section and showing the valve, respectively, in open and closed positions; Fig. 5 is a side elevation, parts being shown in section, of a detailed apparatus, the essentials 85 of which are diagrammatically shown in Fig. 1; and Fig. 6 is an end elevation of the same, parts being shown in section.

The apparatus illustrated has two sets of coal retorts 1, 2, 3, and 4, and 5, 6, 7, and 8, respectively, which contain the coal or other 90 carbonaceous material used in the production of the gas. The retorts 1, 2, 3, and 4, are connected at their bottoms and tops respectively by conduits 9 and 10 with the combustion chambers 11, 11^a, 11^b, and 11^c, and the retorts 5, 6, 7, and 8 are likewise connected at their 95 bottoms and tops by conduits 12 (shown in dotted lines, Fig. 1) and 13 with similar combustion chambers 14, 14^a, 14^b, and 14^c, the two sets of combustion chambers being 100 connected at their tops by a pipe 15 and the bottom conduits 9 and 12 by the transverse pipe 15'. These combustion chambers are arranged to contain a metallic oxid, such as 105 the magnetic oxid of iron before mentioned. 110

The first set of coal retorts 1, 2, 3, and 4, is also connected at bottom and top by conduits 17 and 18 with regenerative chambers 19, 19', arranged in tandem and containing checker work, which in turn are connected with a gas receiving receptacle 20 having a discharge pipe 21 through which gas is discharged to a suitable storage tank through an automatic relief valve 22. The second set of coal retorts 5, 6, 7, and 8, is also connected at bottom and top by conduits 23 and 24, with regenerative chambers 25, 25', arranged in tandem which in turn are connected with a gas receiving receptacle 26 having a discharge pipe 27 and automatic relief valve 28. The receptacles 20 and 26 are respectively connected by conduits 30 and 31 with the casing of a reversing valve 32, which is connected to a pump 33. The pump operates continuously in one direction, and the valve 32 is automatically and periodically operated to reverse the direction of flow of gas through the apparatus.

Both sets of coal retorts and oxid chambers are connected through valve controlled branch pipes, as clearly illustrated in the drawings, to the upper and lower gas conduits so that as many chambers as are desired may be connected or disconnected from the system. As illustrated the number of oxid chambers corresponds to that of the distillation retorts. Such an arrangement makes it possible to cut into or out of the system any desired number of retorts or combustion chambers thus securing economical operation and an exact balancing of the system and effecting the chemical changes in the gases by passing the same in a plurality of small streams rather than a single one of greater volume, hence bringing the gases into more intimate contact with the carbonaceous material and oxides and securing an increased efficiency.

It is thus seen that two substantially symmetrical sets of coal retorts, ore or combustion chambers, and receptacles are provided which are connected together and associated with a pumping apparatus so that gas may be caused to flow from one to the other in the desired number of separate streams.

The apparatus is arranged so that no matter in which direction the gas is flowing the flow is upwardly through both sets of coal retorts. In order to insure this direction of flow, check valves are arranged at suitable points in the system, as will be explained.

These check valves are illustrated in Figs. 2, 3, and 4. Each comprises a frame 34 carrying a bearing projection 35 in which is pivoted a valve member 36. When gas flows from left to right (as the valves are illustrated in the drawing) the valve mem-

ber 36 is moved to open position, as shown in Fig. 4. When the gas flows in the reverse direction the valve is maintained in closed position, as shown in Fig. 2. These check valves are illustrated in the diagrammatic view Fig. 1, by sleeves on the conduits, the open and closed positions of the valves being indicated by circles on the top of the sleeves with a line through their diameter. When the line is parallel with the conduit it indicates that the valve is open, and when it is at right angles to the conduit, that the valve is closed.

With the check valves in the positions indicated in Fig. 1 the gas will flow from the first set of coal retorts 1, 2, 3, and 4 to the oxid chambers 11 to 11^e and 14 to 14^e and its course is as follows:

The pump 33 forces gas from the receptacle 20 through the chambers 19, 19', through the check valve 38, which is in open position, through the conduits 17 and 39 and upwardly through the coal retorts 1, 2, 3 and 4. The flow of gas from the chamber 19 upwardly through the conduit 18 is prevented by the check valve 40 which is closed when gas tends to flow in this direction. The gas is also prevented from flowing directly from the conduit 17 through the conduit 9 to the ore chamber 11 to 11^e by the check valve 41 which is closed when the gas tends to flow in such direction. Consequently the gas must flow upwardly through the first set of coal retorts, from which it passes through the conduit 10 and through a check valve 42, which is in open position, to the ore chambers. The gas from the receptacle 20 and the regenerative chambers thus passes upwardly through the first set of coal retorts to the ore chambers carrying with it the gas generated in the retorts. The retorts are normally filled with coal, so that no volume of gas exists therein except the gas being generated which quickly passes to the conduits and the oxid chambers.

From the conduit 10 a portion of the gas flows downwardly through the ore chambers 11 to 11^e, thence through the pipe 15' to the conduit 12 while the remaining portion flows through pipe 15 then downwardly through chambers 14 to 14^e to conduit 12, the combined portions passing through check valve 43 to the pipes 44 and upwardly through the second set of coal retorts 5, 6, 7, and 8. Gas is prevented from flowing from the top of the chambers 14 to 14^e and through the conduit 13 by a check valve 45 which is closed when the gas tends to flow in this direction. The gas is also prevented from flowing directly from the conduit 12 through the conduit 23 to the regenerative chambers 25, 25', by a check valve 46 which is closed when the gas tends to flow in this direction. Consequently the

gas is forced to flow from the combustion chambers upwardly through the second set of coal retorts and out through a check valve 47, which is in open position, to the conduit 24 and the regenerative chambers 25, 25', and receptacle 26. The gas is prevented from flowing back through check valve 45, because the pressure of the gas is equal on both sides of the valve.

10 When the reversing valve 32 reverses the direction of flow of gas in the apparatus, the entire series of check valves reverse their positions, as will be readily understood, thereby causing the gas to flow from 15 the receptacle 26 and the regenerative chambers 25, 25', through the valve 46 and conduit 23 upwardly through the second set of coal retorts 5, 6, 7, and 8, through the oxid chambers 14 to 14° and 11 to 11°, and thence 20 through conduit 9 upwardly through the first set of coal retorts 1, 2, 3, and 4, and through conduit 18 to the regenerative chambers 19, 19', and receptacle 20.

From this brief description of the apparatus it will be clear that a closed system 25 has been provided in which the direction of flow of gas is periodically reversed and upon such reversals is caused to follow a definite course through the receptacles, regenerative chambers, coal retorts, and combustion chambers.

When the gas producing process is first started it is necessary to heat the retorts by some suitable means such as by initially 30 burning a part of the coal in the retorts but, after the process has been started, it is no longer necessary to do so, the heat of the process itself being utilized for this purpose.

40 The coal retorts and also the other principal elements of the system are provided with heat insulating linings 50 which prevents material loss of heat by radiation, and provided with fire brick or other refractory material arranged to absorb the 45 heat of the hot gases flowing therethrough and transfer the same to the coal for heating the latter. The coal retorts are arranged to have the coal charged into the same at the top, and the ashes and other refuse removed from the bottom, without admitting air thereto. As shown in Fig. 5 each retort is charged with coal from a storage receptacle 53, which receptacles 50 communicate with the top of the retorts through conduits 54 and valves 55, and which storage receptacles of each set are in turn supplied from a hopper 56 through pipes 57 and valve 58. When the retorts 55 are to be charged the valve 58 is opened and the storage receptacles 53 are filled with coal from the hopper 56, each storage receptacle preferably containing the proper quantity of coal for a single charge of the 60 retort. Valve 58 is then closed to prevent

air entering the storage receptacles, and valve 55 then opened to admit the coal to the retort. Each coal retort communicates through pipe 59 and valve 60 with a discharge hopper 61, common to the set, 70 whereby the passage of ashes and other refuse from the retort to the discharge hopper may be controlled at will.

The interiors of the oxid chambers 11 to 11° and 14 to 14° are provided with a plurality of distributing passages, in the nature of pans 64 composed of specially shaped refractory blocks which are provided with openings therethrough, the successive pans being so located relative to one another that these pans are staggered with relation to one another, thereby providing a series of irregular passages from the top to the bottom which causes the ore to be thoroughly distributed and causing a maximum amount of ore to be exposed to the gas in said chamber.

The bottoms of the oxid chambers communicate through conduits 65 and valves 66 with discharge hoppers 67. The tops of 90 these oxid chambers communicate through valves 68 and pipes 69 with storage receptacles 70 which are supplied with the metallic oxid from hoppers 71 through the distributing valves 72. Consequently each passage through the oxid chambers can be supplied with a measured amount of oxid, from the receptacles 70, without admitting air, and likewise the metallic iron resulting from the reduction of the oxid can be removed 100 from the oxid chambers into the discharge receptacles 67 without admitting air.

Assuming that the retorts have been heated sufficiently for distillation and that gas has been generated, in sufficient quantity to 105 drive all the air out of the system, the cycle of events is as follows:—

The gas generated in the first set of coal retorts comprises principally carbon monoxid (CO) and hydrocarbons, but because 110 of the limited amount of oxygen the volume of carbon monoxid is relatively small. These gases pass to the sets of ore chambers where the carbon monoxid (CO) unites with the oxygen (O₂) of the iron oxid (Fe₃O₄) forming CO₂, causing combustion to take place and producing heat which breaks up the hydrocarbons and also raises the temperature of the gas.

The flow of gases from the coal retorts to 120 the combustion chambers causes the hot gases comprising (CO₂) hydrogen (H₂) and other gases which were in the oxid chambers to be forced from the chambers upwardly through the second set of coal retorts where 125 the carbon dioxid (CO₂) is converted into carbon monoxid (CO) when it comes in contact with the heated carbon or coal in the retorts.

The heat of the gases acquired in the com- 130

bustion chambers is absorbed by the fire brick interior of the second set of coal retorts and consequently the coal is maintained at a suitable temperature for carrying out the process, the entire apparatus being heat-insulated by providing the conduits and retorts with suitable magnesia linings.

The gases, which have passed through the second set of coal retorts, consist principally of carbon monoxide, hydrogen, and a small amount of other gases, and these pass to the regenerative chambers 25, 25', where their excess heat is absorbed by the checker-work in the regenerative chambers as the gases flow therethrough to the receptacle 26. When the gases arrive in the receptacles 26 a portion of them may escape through the relief valve 28 to the storage tanks as the pressure of the gas generated in the system becomes sufficient to cause the gas to flow through the relief valve. Other portions of the gas may flow in the reversing valve 32 and through the pump to the receptacle 20 and be further forced through the system. The timing of the reversing valve 32, however, is determined so that the gases pass approximately through only one cycle, after which the valve is reversed, causing them to flow in the opposite direction.

When the valve is reversed, the gases in receptacle 26 are forced through the regenerative chambers 25, 25', where they are heated by the hot checker work in case they have lost any of their heat in the receptacle 26, and from the chambers 25, 25', they pass upwardly through the second set of coal retorts 5, 6, 7, and 8. The coal in this set of retorts has been heated by the passage of hot gases therethrough and by the heat of the walls of the retorts and consequently gas is continually being generated from said coal, which gas flows with the other gases to the combustion chambers 14 to 14^c and 11 to 11^c where the carbon monoxide unites with the oxygen of the iron oxid to form CO₂, producing heat and breaking up the hydrocarbons. The hot gases in the combustion chamber which came originally from the first set of coal retorts are forced back to said retorts, where the heat of the gases is utilized to maintain the temperature of the coal and the retorts and the carbon dioxide is converted to carbon monoxide which flows with the hydrogen and other gases to the regenerative chambers 19, 19', through the checker work therein which is heated by the passage of the gases to the receptacle 20.

It will thus be seen that the gases generated in the coal retorts, which gases comprise principally carbon monoxide and hydrogen substantially free of nitrogen, are passed to combustion chambers where oxygen is furnished to increase the volume of the gases, produce heat and break up the hydrocarbons. This increased volume of

hot gases is then returned to the coal retorts, where the carbon dioxide is changed to carbon monoxide and at the same time the coal and the coal retorts are heated to a proper temperature to cause this change to take place and also to distil the coal. The heat generated in the combustion chambers is utilized to heat the coal in the coal retorts by causing the gases to be periodically oscillated from the coal retorts to the oxid-chambers and back again. In other words, it may be considered that, at one instant, gas is being generated in one set of coal retorts, passed to the sets of combustion chambers where its volume is increased and heat produced, and at the same time hot gases previously in the combustion chambers are forced through the second set of coal retorts to heat the retorts and coal and to convert the carbon dioxide into carbon monoxide. At the next instant the direction of flow is reversed and the hot gases in the combustion chambers are returned to the first set of coal retorts, where their condition is changed and their heat utilized for generating more gas from the coal. At the same time the gases generated in the second set of coal retorts are forced to the combustion chambers, where they unite with the oxygen of the iron oxid.

In addition, the heat of the gases is conserved by regenerative chambers arranged in tandem, which store the heat of the hot gases flowing out of the system and convey it to any gases flowing into the apparatus from the receptacles. The gases first enter regenerator 19 or 25 and then pass to the adjacent regenerator 19' or 25' from which it is delivered to the receptacles 20 or 26. By providing a series of small diameter and comparatively high regenerators arranged in tandems, an excellent abstraction of heat is effected, the second regenerator always remaining at a lower temperature than the initial regenerator to which the gas is led from the retorts.

The heat of the process is further conserved as follows:—

The removal of the oxygen from the iron oxid in the combustion chambers leaves free iron, which is relatively hot and which, in its hot condition, is discharged from time to time to the atmosphere. As the free iron comes into contact with the air, it re-oxidizes, forming iron oxid, and producing heat. As a matter of fact, when the iron discharges from the combustion chambers it is dark in color, but as soon as it comes in contact with the air it begins to glow as it unites with the oxygen to form iron oxid. The heat of the iron and the iron oxid is utilized for warming the coal charged into the coal retorts by causing the hot iron and iron oxid to pass through conduits or ore drums which are surrounded

by coal. The apparatus for carrying out this step of the process is illustrated in Figs. 5 and 6 and is as follows:

The discharge hoppers 67 of the oxid chambers are connected through valves 75 with discharge chutes 76 which discharge into ore drums 77, which are located relative to other drums 78, 79, and 80, all of which are provided with suitable screw or other 10 conveyors so that the hot iron is first conveyed to the drums 77, carried the length thereof and then discharged into the drums 78, carried back through the length of these drums, discharged to the third drums and 15 so on, until from the last drum it is discharged into a pocket 81, from which the iron, which has now been again converted into iron oxid by exposure to the atmosphere, is carried by a bucket conveyor 82, 20 back to the feeding hopper 71. The ore drums 77, 78, 79, and 80, are located within a receiving pocket 83 which is normally kept filled with coal for charging the coal retorts. The heat of the hot iron, as well 25 as that produced by reoxidization of the iron as it passes through the ore drums is communicated to the coal surrounding these ore drums and consequently raises its temperature preliminary to its productive distillation in the coal retorts. This coal is 30 removed from the coal pocket 83 by the bucket conveyor 82 and distributed to the retort feed hoppers 56.

The iron oxid, after giving up its heat, is 35 again reconveyed to the apparatus for charging the combustion chambers and is used over again. The economy of this step of the process will be readily apparent and it will be noted that oxygen is furnished to 40 the gas without permitting non-combustible elements to be supplied thereto at the same time and by means which may be used over and over again and by a process which generates heat that it utilized in carrying out 45 the other steps of the process.

The heat of the free iron and of the oxidation of this iron also serves a useful purpose in eliminating the sulphur which comes from the coal. This sulphur is vaporized 50 in the coal retorts and passes to the ore chambers where it forms sulphurous acid. This acid is discharged with the free iron and when the temperature of the iron is raised by oxidation it is decomposed, forming SO_2 , which is a vapor, water, and oxygen. The heat in the combustion chambers is not sufficient to thus decompose the sulphurous acid, but the heat of the re-oxidation of the iron is sufficient to so decompose it. Consequently the iron oxid which 55 is recharged into the combustion chambers is free from sulphurous acid and the process thus automatically eliminates the sulphur.

From the foregoing description it will

be clear that a process has been devised by means of which a fuel gas rich in carbon monoxid and hydrogen but substantially free from non-combustible elements such as nitrogen, is produced in an automatic 70 and continuous manner and in such a way that the heat of the process is utilized for making the process self-sustaining. The sulphur in the coal is automatically eliminated and the oxygen carrying element is 75 automatically regenerated so that it may be used over and over again. The process is simple, economical, automatic, and continuous, as will be readily observed. Moreover, the size of the apparatus is reduced 80 over that ordinarily required in such processes because of the fact that the oxygen is not furnished by means of air. Air is a mixture containing substantially one part of oxygen to four parts of nitrogen, and 85 consequently an apparatus in which oxygen is furnished by the air must be of sufficient size to accommodate four volumes of nitrogen to one volume of oxygen.

The process is particularly economical 90 and efficient because of the utilization of the heat generated in furnishing the oxygen for carrying out the process, thus making the process self-sustaining and eliminating the expense of heating the various retorts 95 and chambers, as heretofore required.

It is to be understood that variations may be made in the exact manner of practicing the process, such variations being included within the scope of the appended 100 claims.

What is claimed is:—

1. The method of producing gases rich in carbon monoxid and hydrogen but substantially free of nitrogen, which consists in distilling carbonaceous material without exposing the same to air, passing the resulting gases into contact with a metallic oxid to furnish oxygen to the gases and produce heat, repassing the hot oxidized gases into contact with the carbonaceous material to furnish carbon to the gases, and passing the free metal resulting from the oxidation of the gases into heat exchanging relation with the carbonaceous material used in the process to warm said carbonaceous material and utilize the heat of the metal. 110

2. The method of producing gases rich in carbon monoxid and hydrogen but substantially free of nitrogen, which consists in distilling coal without exposing the same to air, passing the resulting gases into contact with an iron oxid to furnish oxygen to the gases and produce heat, repassing the hot oxidized gases into contact with the coal to furnish carbon to the gases and heat the coal, and passing the free iron resulting from the oxidation of the gases into heat exchanging relation with the coal used in 120 125 130

the process and also exposing the iron to air whereby the heat of the iron is used for warming the coal and iron is converted into iron oxid for subsequent use in the process.

3. The method of producing gas rich in carbon monoxid and hydrogen but substantially free of nitrogen, which consists in distilling carbonaceous material without exposing the same to air, passing the gases resulting from the distillation into contact with a metallic oxid to furnish oxygen to the gases and produce heat, passing hot oxidized gases into contact with carbonaceous material to furnish carbon to the gases and heat the carbonaceous material, periodically reversing the direction of flow of the gases whereby the heat generated in oxidizing them is utilized for heating the carbonaceous material, and passing the heated metal resulting from the oxidation of the gases into heat exchanging relation with the carbonaceous material used in the process.

4. The method of producing gases rich in carbon monoxid and hydrogen but substantially free of nitrogen, which consists in distilling coal in closed retorts without exposing the coal to air, passing the resulting gases into contact with a metallic oxid in a closed chamber to furnish oxygen to the gases and produce heat, passing the hot oxidized gases into contact with the coal in the closed retorts to furnish carbon to the gases and heat the coal, periodically reversing the direction of flow of the gases whereby the heat generated in oxidizing them is utilized for heating the coal, passing the metal resulting from the removal of the oxygen from the metallic oxid into heat exchanging relation with the coal used in the process and exposing said metal to air whereby the metal is changed into a metallic oxid and its heat absorbed by the coal, periodically supplying the warm carbonaceous material to the retorts, and periodically supplying the revived metallic oxid to the oxid chambers.

5. The method of producing a gas rich in carbon monoxid and hydrogen and substantially free of nitrogen, which consists in producing gases by distilling carbonaceous material out of contact with air, furnishing oxygen to said gases and generating heat by passing the same in a plurality of divided streams into contact with a metallic oxid, passing the hot gases into contact with carbonaceous material and subsequently through an excess heat-absorbing chamber, and periodically reversing the direction of flow of the gases whereby the heat of oxida-

tion is utilized for distilling the carbonaceous material without the necessity of applying external heat.

6. The method of producing gases rich in carbon monoxid and hydrogen but substantially free of nitrogen which consists in distilling carbonaceous material without exposure to air, passing the resulting gases in a plurality of separate streams into contact with a metallic oxid to furnish oxygen to the gases and produce heat, repassing the hot oxidized gases into contact with the carbonaceous material to furnish carbon to the gases, and passing the free metal resulting from the oxidation of the gases into heat exchanging relation with the carbonaceous material used in the process to warm said material and utilize the heat of the metal.

7. The method of producing a gas rich in carbon monoxid and hydrogen and substantially free of nitrogen, which consists in producing gases by distilling carbonaceous material out of contact with air, furnishing oxygen to said gases and generating heat by passing the same in a plurality of divided streams into contact with a metallic oxid, passing the hot gases into contact with carbonaceous material and subsequently through excess heat-absorbing chambers arranged in tandem, periodically reversing the direction of flow of the gases to utilize the heat of oxidation to distill the carbonaceous material, and passing the free metal resulting from the oxidation of the gases into heat exchanging relation with the carbonaceous material to warm said material and utilize the heat of the metal.

8. The method of producing a gas rich in carbon monoxid and hydrogen and substantially free of nitrogen, which consists in producing gases by distilling carbonaceous material out of contact with air, furnishing oxygen to said gases and generating heat by passing the same into contact with metallic oxid in the form of iron ore, passing the hot gases into contact with carbonaceous material, periodically reversing the direction of flow of the gases to utilize the heat of oxidation for distilling the carbonaceous material without the necessity of applying external heat, and periodically removing the sulphur content of the iron ore by oxidizing the metal resulting from the oxidation by exposing the same to the atmosphere.

In testimony whereof, I sign my name.

CARL LUNDIN.
